UNITED STATES PATENT OFFICE.

GUY MAFERA, OF BOSTON, MASSACHUSETTS.

SPRING-BED FRAME.

SPECIFICATION forming part of Letters Patent No. 574,742, dated January 5, 1897.

Application filed March 9, 1896. Serial No. 582,308. (No model.)

To all whom it may concern:

Be it known that I, GUY MAFERA, of Boston, in the county of Suffolk and State of Massachusetts, have invented certain new and 5 useful Improvements in Spring-Bed Frames, of which the following is a specification.

This invention relates to metallic frames for holding spring bed-bottoms, and particularly to the angular connecting-piece which 10 connects the side rails of a metal bedstead with the elevated cross-bars, which extend across the bed at the head and foot to support the spring bed-bottom fabric or structure.

The invention has for its object to provide 15 a simple and efficient device for the purpose mentioned; and it consists in the improvements which I will now proceed to describe and claim.

Of the accompanying drawings, forming a 20 part of this specification, Figure 1 represents a perspective view of a portion of a metal bedstead or frame embodying my invention. Fig. 2 represents a section on line 2 2 of Fig. 1. Fig. 3 represents a section on line 3 3 of 25 Fig. 2.

The same letters and numerals of reference indicate the same parts in all the figures.

In the drawings, *a* represents one of the side rails of a metal bedstead, the same extending from the head to the foot of the bed, and *b* represents one of the raised cross-bars which extend across the bed at the head and foot to support the spring fabric or structure, which is suitably engaged with said 30 cross-bars and is suspended thereby above the level of the side bars *a* in a manner which is well known and needs no further explanation. In carrying out my invention I connect the side bars *a* with the cross-bar *b* by means 35 of an angular connection or coupling *c*, which comprises the integral lower socket portion 2, formed to receive one end of a side bar *a*, and has a projecting tenon 3, formed to enter a suitable socket in one of the end frames of 40 the bedstead. The connection or coupling *c* is also provided with the integral elevated socket 4, arranged at a right angle to the socket 2 and formed to receive one end of the cross-bar *b*, said socket having in one side a 45 slot 5, through which passes a bolt 6, whereby the cross-bar is adjustably secured to the socket, provision being thus made for adapting the socket to the width of the bed.

The bars *a* and *b* are preferably made angular or L-shaped in cross-section, as shown 55 in Figs. 2 and 3; and the socket 2 is formed so that the salient angle of the side bar *a* is presented at the outer and upper portion of the bed-frame, thus giving the latter a more symmetrical appearance than would be the case 60 if the said angle were at the inner and lower portion, as usual in metallic bed-frames.

Owing to the coupling being formed of a single piece of metal, the sockets 2 and 4 being integral with each other, no bolts are employed for connecting the parts other than that which provides for the adjustment of the upper cross-bar *b* according to the width of the bedstead. The edges of the sockets are bent over the edges of the bars *a* and *b*, as 70 shown in Figs. 2 and 3, and are thus secured thereto without bolts and screws in such manner that they can be applied to the bars or removed therefrom by endwise movement.

I claim—

1. An angular connecting-piece or coupling for the side and end rails of metallic bedsteads, the same comprising the sockets 2 and 4 integrally connected and extending at right angles to each other in different planes, each 80 of said sockets being angular in cross-section and having its edges provided with internal grooves or ways adapted to receive the edges of the side and end rails, and one of said sockets having a tenon 3.

2. The combination with the side and end rails *a* and *b* composed of bars of metal L-shaped in cross-section, of the coupling *c* having the integral sockets 2 and 4 extending at right angles to each other from opposite ends 90 of the portion *c*, each of said sockets being angular in cross-section and having its edges provided with internal grooves or ways adapted to receive the edges of the rails *a* and *b*, the socket 2 having the end tenon 3 and the 95 socket 4 being provided with the slot 5, and the bolt 6 passing through said slot into the rail *b*, substantially as described.

In testimony whereof I have signed my name to this specification, in the presence of 100 two subscribing witnesses, this 7th day of February, A. D. 1896.

GUY MAFERA.
